UNITED STATES PATENT OFFICE.

IGNAZ KICAK, OF PITTSBURG, PENNSYLVANIA.

RAIL-JOINT.

SPECIFICATION forming part of Letters Patent No. 730,130, dated June 2, 1903.

Application filed March 10, 1903. Serial No. 147,078. (No model.)

To all whom it may concern:

Be it known that I, IGNAZ KICAK, a resident of Pittsburgh, in the county of Allegheny and State of Pennsylvania, have invented a new and useful Improvement in Rail-Joints; and I do declare the following to be a full, clear, and exact description thereof.

My invention relates to rail-joints, and has special reference to that class of rail-joint in which the end of one rail is fitted directly into or onto the end of the other rail.

My invention has for its object to provide a simple and cheap form of rail-joint which can be put together without any extra labor or expense, as well as one which will lessen the tendency of the bolts, nuts, and fish-bars from becoming loosened, and one which will form practically a continuous rail, so as to overcome the knocking and jarring between the rails and at the same time allow for expansion and contraction of the rails.

My invention consists, generally stated, in the novel arrangement, construction, and combination of parts, as hereinafter more specifically set forth and described, and particularly pointed out in the claims.

To enable others skilled in the art to which my invention appertains to construct and use my improved rail-joint, I will describe the same more fully, referring to the accompanying drawings, in which—

Figure 1 is a perspective view of the end portion of one T-rail, having in dotted lines the other end portion connected thereto and illustrating my improved rail-joint for use on railroads. Fig. 2 is a top view of a railroad-track containing such rail-joint. Fig. 3 is a side view of one of the tracks shown in Fig. 2, and Fig. 4 is a perspective view of the end portion of a rail used for traction or street railways and containing my improved joint.

Like symbols of reference herein indicate like parts in each of the figures of the drawings.

As illustrated in said drawings, 1 1' represent the two members or rails forming one side of the track A and are of the ordinary construction of T-rails, having a head 2, base 3, and web 4 joining the head to the base. The one adjoining end a of the rail 1 has the upper part of its head 2 cut away for a portion of its length, as at 5, so as to form the

supporting portion 6 on the lower part of the head 2, and this portion 6 extends from the extreme end face b of the rail 1 back on said head 2 for a short distance and terminates in the abutting end or face 7 on said head, which face 7 is formed so as to extend diagonally and entirely across the upper part of the head 2. The other rail 1' has its base 3, web 4, and lower part of the head 2 cut away for a portion of its length, as at 8, at its adjoining end a', so as to form the tongue-like projecting portion 9 on the upper part of the head 2, which projecting portion 9 terminates in the abutting end or face 10, extending diagonally and entirely across the upper part of said head 2 and on the same angle as the end or face 7 on the rail 1.

The manner of constructing, connecting, and using my improved rail-joint is as follows: Each rail is formed with the supporting portion 6 on one end and the projecting portion 9 on the opposite end thereof, and when it is desired to form the joint B between the rails the two rails 1 1' are brought together on the tie C, so that the projecting portion 9 on the adjoining end a' of the rail 1' will be allowed to rest upon and be supported by the supporting portion 6 on the adjoining end a of the rail 1 and sufficient space left between the diagonal abutting ends or faces 7 and 10 on the heads 2 of the rails 1 1' to allow for the expansion and contraction of said rails. After this is accomplished the rails 1 1' are held and secured together at the joint B by means of the fish-plates 11, which are placed on each side of the joint B and are held in place by bolts 12, passing through the same and through bolts 13 in said rails 1 1' and such bolts having the nuts 14 thereon, as in the ordinary construction.

It will be evident that by having the head of the rails cut diagonally and the web and base cut on a vertical plane in forming the joint a continuous rail will be formed and at the same time space provided between the rails for the expansion and contraction of such rails. The joint is firm and rigid, and the wheels of the rolling-stock always have a firm tread upon each rail before leaving the preceding one or the joint, while at the same time the danger of the nuts becoming loosened and lost from the bolts will be avoided.

What I claim as my invention, and desire to secure by Letters Patent, is—

1. A rail-joint consisting of two meeting members, one of said members having the upper part of its head cut away for a portion of its length to form a supporting portion and extending back to form an end face on and across said head, and the opposite member having the lower part of its head cut away to form a projecting portion having an end face formed on and extending across said head for resting upon the said supporting portion.
2. A rail-joint consisting of two meeting members, one of said members having the upper part of its head cut away for a portion of its length to form a supporting portion and extending back to form a diagonal end face on said head, and the opposite member having the lower part of its head cut away to form a projecting portion having a diagonal end face thereon on the upper part of its head for resting upon said supporting portion.

3. A rail-joint consisting of two members, one of said members having the upper part ²⁵ of its head cut away for a portion of its length to form a supporting portion and extending back to form a diagonal end face entirely across the upper part on said head, said member being provided with a vertical end face ³⁰ on the lower part of said head, web and base, and the opposite member having the lower part of its head cut away to form a projecting portion on the upper part of its head with a diagonal end face entirely across the same ³⁵ for resting upon the said supporting portion, said member being provided with a vertical end face on the lower part of said head, web and base.

In testimony whereof I, the said IGNATZ KI- ⁴⁰ CAK, have hereunto set my hand.

IGNAZ ^{his} X KICAK.
